[57] CLAIM

The ornamental design for a combined food jar scraper and food spreader, substantially as shown and described.

DESCRIPTION

FIG. 1 is a side elevational view of a combined food jar scraper and food spreader, showing my new design as seen from the left-hand side thereof;

FIG. 2 is a front elevational view thereof;

FIG. 3 is a side elevational view as seen from the right-hand side thereof;

FIG. 4 is a bottom plan view thereof;

FIG. 5 is a top plan view thereof; and

FIG. 6 is a rear elevational view thereof.
